UNITED STATES PATENT OFFICE.

CHARLES SCHARL, OF NEW YORK, N. Y.

CONVERTIBLE CLUB FURNITURE.

Application filed June 13, 1922. Serial No. 568,050.

To all whom it may concern:

Be it known that I, CHARLES SCHARL, a citizen of Hungary, and resident of New York, N. Y., in the county of New York and 5 State of New York, have invented certain new and useful Improvements in Convertible Club Furniture, of which the following is a specification.

My invention relates to convertible furniture and has for its main object to provide 10 a device of the mentioned nature which would combine several pieces of furniture in one structure so that said device might be used for a number of purposes, like as a bed, 15 or as a table, or a sofa, or chairs, at different times, or as several of them simultaneously, that is, for more than one of the above mentioned purposes at the same time. It embodies, essentially, a supporting frame structure, 20 made preferably of steel, and a second movable frame structure applied rotatably in said supporting structure and having a foldable table and chairs applied to it. A third frame structure is applied slidably in 25 said supporting structure and in connection with said rotatable frame, for the purpose of automatically holding the bedding and other loose covering pieces for said convertible furniture, and the different parts of said 30 convertible furniture are arranged and connected in such a way as to semiautomatically fit into the positions required for the several uses of said furniture. The invention has further objects which will be apparent as the 35 description of the same proceeds.

For a full description of the invention and the merits thereof and also to acquire a knowledge of the details of the construction of the same for effecting the various results mentioned hereinbefore reference is to be had to the following description and accompanying drawings.

While the essential and characteristic features of the invention are susceptible of modification, still the preferred embodiment of the invention is illustrated in the accompanying drawings, in which:—

Fig. 1, is a side elevational view of the convertible furniture, the table and one of the chairs being shown in the position when used, the other chair being shown in a folded position, as when out of use, while the rotatable frame composing the bed device of the furniture is shown in the vertical position as when not used for a bed. In this figure as well as all other figures my device is shown

in a skeleton way, that is only the structural and mechanical elements of the same are shown without any covering, finishing, upholstering, or beddings. These auxiliary attachments and finishings can be executed and attached to the structure shown in any manner suitable to the user; they do not pertain to the merit of the invention, and I have omitted them from my drawings in order to 60 serve the clearness of them.

Fig. 2, is a plan view of my device, the bed frame being folded down into the position when it is used as a bed,

Fig. 3, is a side view of my device, showing the chairs and the table in a position as when used, the bed frame serving as a back for said chairs, and the sliding frame, behind the bed frame, being raised to hold the bedding,

Fig. 4, is a detail view of a sliding device used in connection with the table piece of my invention,

Fig. 5, is another detail view, showing the connections between the bed frame and the 70 sliding frame,

Figs. 6, 7, and 8, are detail views of certain parts of my device.

Referring more closely to the drawings, 9 indicates the supporting base structure which is preferably made of standard structural irons, and is of a narrow longitudinal shape. The base structure is movable on casters 10 or other anti-friction devices applied to the lower ends of legs 11. The bed frame 12 is 90 applied to said base frame 9 and is rotatable in it on pins 13. A table 14 and two chairs 15, 15' are hingedly applied to the lower surface of said bed frame and to the base frame, respectively; the table is in the center and the two chairs at either side of same. The two chairs have rest pieces 16, 16' firmly attached to them at their outer ends, thus forming two end pieces for my furniture when it is placed in a position to be used as 100 a bed or also when it is used as a table and chairs. The chairs 15 have legs 17 hingedly connected to the base frame of my convertible furniture by connecting rods 18 in such a manner that they can be opened up to 105 firmly support the chair as shown in Fig. 3 or folded up when not in use as shown on the left hand side of Fig. 1. In a somewhat similar manner, table 14 is connected to the base frame through connecting rod 19, the 110 lower end of which is attached hingedly to the base frame, while the upper end has a

sliding sleeve 20 running on a rod 21, secured to the lower surface of the table, through securing means 22, thereby automatically insuring the opening of the table 5 in case the bed frame 12 is put into a vertical position and the folding of the same when the bed frame is placed into a horizontal position. In case the bed frame is put in a vertical position for the purpose of storing the 10 furniture, table 14 can be folded upwardly, out of use, insuring very reduced space requirements for the furniture in a horizontal direction. In the latter case, chairs 15 will be similarly folded upwardly to vertical bed 15 frame 12, the side arm pieces 16 rotating with the folded chair 15 and disappearing into the openings in the base frame as will be explained more in detail.

An extension frame 23 is attached to the 20 back of the base frame 9 and a longitudinal space 24 is thereby formed between base frame 9 and said extension frame 23, in which a holding frame 25 may slide in an upward or downward direction. A shorter 25 frame 27 is hingedly applied to the top edge of frame 25 and may be folded down upon the same, as shown by the full lines in Fig. 3, or it may be opened up, for certain purposes to be explained presently, and as indicated by the dotted line position of the 30 same in said figure. The main purpose of frame 25 is to catch and hold the bedding applied to bed frame 12 when said frame is in a vertical position, and when the furniture is used for other purposes than a bed. There are automatic inter-connections between the holding frame 25 and bed frame 12 to insure that said holding frame will automatically disappear in case the furniture 35 is used as a bed and same may be automatically raised to the position shown on Fig. 3, and adapted to hold the bedding when the furniture is not used as a bed. These automatic connections consist of certain levers, chains, and pulleys. Rotatable levers 29 are applied to the back of the bed frame 12 (Fig. 3) rotating around pins 30, applied to bed frame 12, but are independent of said frame. A longitudinal piece 31 connects the two end levers 29 (Fig. 2) and forms a frame structure with the same. To insure a more uniform action, additional 40 rotating levers 32 are applied to the reinforcing members 33 of the bed frame and hingedly joined to them (Figs. 2, 6, and 7). Said intermediate levers 32 are also connected to the longitudinal piece 31 and rest normally on uprights 34. A chain 35 is secured to the lower end of bed frame 12, as at 36, and also to the lower end of holding frame 25, as at 37. The chain is led through pulley 38 (Figs. 3 and 5), attached to the lever 29. Similar chains and pulleys are working between bed frame 12 and holding frame 25 at the two ends of said frame in

connection with levers 29 and in between, at spaced intervals, in connection with levers 32, thereby insuring a uniform and reliable movement to frame 25.

Frame 12 may have mattresses 39 attached to it and covers, pillows and other further necessary beddings applied to them so as to make it a ready, perfectly usable bed if placed in a horizontal position as shown with dotted lines in Fig. 3. When frame 12 is placed horizontally, the end 36 and chain 35 will move upwardly and the chain will move around pulley 38 downwardly so that frame 25 will slide by its own weight into the space 24 and disappear in the back of the structure, making a perfect horizontal bed surface for my convertible furniture. The chairs 15, 15' will drop into a horizontal position by their own weights, resting on legs 17, or they may be opened up into such position and give additional firm support to the bed frame.

Arm pieces 16 will serve as head and foot of the bed, respectively.

In case I want to use my convertible furniture as a table and a pair of arm chairs, I swing the frame 12 upward around pins 13 in a slightly slanting vertical position as shown in Fig. 3. The mattresses and the rest of the bedding, that is the loose coverings, pillows, etc. will tend to slide off downwardly, which tendency nevertheless will be counteracted by the frame 25 moving up from behind the base frame 9. As the outer end of the frame 12 is swinging upwardly, the lower one, marked 36 will move downwardly and will move the frame 25 upwardly out of the space 24 provided for the same through the action of the chains 35. The frame 25 therefore will gradually and gently catch the bedding and keep it in a similar position as when in use so that at a subsequent opening of the convertible furniture to be used as a bed, all the necessary bedding will again be in its place.

After having moved the bed frame into its vertical tilted position and having stored the bedding between said frame and the holding frame 25, I now may open the table 14 which has two hinges 14' on the bed frame and have it rest on its swinging and sliding lever 19. In a similar way I may open the chairs 15 and let them rest on their levers 18 and legs 17. With the rests 16 as detailed hereinbefore, I now have a table and two armchairs with a comfortable back, the latter one formed by frame 12. The table, the chairs and their arm rests, as well as the underside of the frame 12 serving as the back for them, may be finished and ornamented in any way suitable to the user. In order to keep the frame in its position, rests 39 are provided at reinforcing member 40 of the base frame structure 9. A further security for holding the frame 12

and the chairs in a rigid position against one another is the construction applied to either side of the bed frame 12 and composed of coacting sleeves 41 on the bed frame 5 and on the inner surface of the arm rests 16, respectively, and bolts 42 which can be secured together in a similar way to that used on the hinges of a door and released when the bolts 42 are removed. Bolts 42 10 are secured by chains 43 hanging on them when out of use.

I finally may also use my convertible furniture as an ornamental sofa adapted to be used for sitting and resting during the day. 15 In order to bring the same into this form, I swing the bed frame 12 downwardly into a horizontal position like when using the same for a bed and as indicated in Fig. 3 in dotted lines. In this case however I do 20 not let holding frame 25 slide downwardly into the space 24 but my device will automatically lift the same above the level of the bed. I then lean the lower edge of it against supporting structure 26, open the 25 folding upper frame 27 and rest it on the bed surface as shown in Fig. 3 in dotted lines, thereby forming a comfortable rest similar to those employed on sofas. The loose bedding and coverings for the bed may be made 30 so, that part of them may be folded up and over the frames 25 and 27 thereby giving my furniture the appearance of a perfect sofa and contributing to the comfort that may be derived from the same. The automatic lifting of the frame 25 in case of using my furniture as a sofa is executed the following way: The lower ends of the chains 43 holding the bolts 42 are secured to the 35 swinging levers 29. When the furniture is to be used as a sofa the bolts 42 are applied into the sleeves 41 on the sides of the bed frame 12 without connecting the same to the sleeves on the sides of the arm rests 16. The chairs are opened with their legs and 40 arm rests and the frame 12 brought into the horizontal bed position. Connecting the chains 43 however as explained hereinbefore, will cause the levers 29 and frame 31 to move upwardly into the position shown 45 in Fig. 3 in dotted lines, chains 35 and pulleys 38 will move into the positions 35 and 38 thereby lifting the lower edge of frame 25 to the upper level of the bed and said edge can now be leaned against the upper 50 edge of the structural piece 26 and brought into the position necessary for making a sofa out of a bed.

If I do not desire to use my furniture in any of its three positions, it can be folded 55 up into a relatively very small space (my preferred embodiment requires only sixteen inches space in width when folded) and stored or kept alongside any wall or in any corner of the room. In this case the 60 bed frame is brought into its vertical po-

sition without using the sofa attachment so that frame 25 will catch and hold the loose bedding, and the table and chairs are folded upwardly to the lower surface of the bed frame, arm rests 16 swinging backwardly 70 and downwardly and disappearing into spaces 44 provided for this purpose in base frame 9. One of the characteristic and distinguishing features of my convertible furniture is that it uses the very same space 75 of the room as a bed, a sofa or a table and arm chairs, according to the necessity.

As will be seen from the above description and by inspecting the accompanying drawings, my invention has many distinct 80 improvements and merits and I do not want my convertible furniture to be classed with the usual folding style of devices. There are no parts to be folded in this furniture which would be destroyed by the steady 85 wear and tear accompanying such repeated foldings and flattenings. All the parts are easy and free to access for inspection and for repairs or are easily removable, like 90 the beddings and the mattresses. The air and the sunshine can reach every part of my furniture and no dust can collect in the same, it therefore is as sanitary as any such furniture can be. In every position of its uses it is aesthetic and it is so when 95 folded up for storage. Another improvement that I employ in my convertible furniture is that the central part of the mattresses, which I employ in three sections 100 fitting into suitable openings in the bed frame 12, is a perfect square and can be turned around into always new positions so that the wear and tear of the same will be uniform. For a similar reason the two side 105 sections of the mattresses can be easily exchanged with one another.

A further advantage of my convertible furniture against most of those used heretofore is that it has not straps and other parts which may easily deteriorate in use 110 and that all its actions are automatic, automatically holding the beddings and loose parts in the required positions without folding them and performing its several duties with very little and very convenient personal 115 attention of the user.

Since lately the housing facilities are always more and more restricted and the apartments, above all in large cities, very 120 much reduced and built with smaller rooms, a furniture of the style as described hereinbefore would meet a very acute necessity, at the same time contributing to the comfort of the large masses of the public which 125 can not afford to have all the different pieces of furniture that are combined in my device. My furniture can be manufactured at a very low cost since all its parts are simple and of standard make and will make such a furniture accessible even to those whose finan-

cial means are very moderate. I finally consider my furniture as an ideal for clubs, barracks, boys' camps, institutions, etc., where the same space can be used in different ways during the day and at night, with a very negligible amount of effort and work necessary. Again, in case of the need for a larger free space my convertible furniture can be stored or set aside and again used very comfortably and easily.

Having thus described my invention, what I claim as new and want to protect by Letters Patent is:

1. In a convertible furniture, the combination of a base frame with a bed frame, said bed frame being rotatably applied to said base frame, of a holding frame slideably applied into said base frame and of means to inter-connect said bed frame to said holding frame in such a manner that said holding frame will slide upwardly when said bed frame is moved into a vertical position and will slide downwardly when said bed frame is brought into a horizontal position.
2. In a convertible furniture, a base frame, a bed frame, applied rotatably into said base frame, a holding frame applied slideably into said base frame and means to connect

said bed frame to said holding frame, said means comprising an oscillating lever applied to said bed frame, a pulley at the end of said lever and a chain lead around said pulley and connecting the lower portions of said holding frame and said bed frame.

3. In a convertible furniture, a base structure, a bed frame rotatably applied on said base structure, a holding frame vertically and slideably applied in said base structure, a rotatable lever applied to said base structure, a pulley on said lever, a chain connecting the lower ends of said holding frame and said bed frame and applied around said pulley, a second chain detachably connecting said bed frame to said lever, a hingedly connected second frame applied to the upper edge of said holding frame, and a longitudinal member arranged on said base structure alongside of said holding frame upon which the lower edge of said holding frame can be placed and said frame brought into a position forming a back support.

Signed at New York, in the county of New York and State of New York this 19th day of May A. D. 1922.

CHARLES SCHARL
